[57] CLAIM

The ornamental design for a bass drum, substantially as
shown and described.

DESCRIPTION

FIG. 1 is a front, top and right side perspective view of
a bass drum showing my new design;

FIG. 2 is a front elevational view;

FIG. 3 is a left side elevational view;

FIG. 4 is a top plan view; and

FIG. 5 is a rear elevational view.

In FIGS. 1-3 and 5 the mounting tube is shown as broken
in order to indicate indeterminate length.FIG. 1
